LEON B. HILLS, OF LAKESIDE, OHIO, ASSIGNOR, BY MESNE ASSIGNMENTS, TO
NATIONAL CARBON COMPANY, INC., A CORPORATION OF NEW YORK.

MOLD FOR STORAGE-BATTERY GRIDS.

1,387,926.

Specification of Letters Patent. Patented Aug. 16, 1921.

Application filed November 20, 1918. Serial No. 132,316.

To all whom it may concern:

Be it known that I, LEON B. HILLS, a citizen of the United States, and resident of Lakewood, in the county of Cuyahoga and State of Ohio, have invented a certain new and useful Improvement in Molds for Storage-Battery Grids, of which the following is a full, clear, and exact description.

This invention relates to molds for storage battery grids or electrodes and one object is to design a mold of such structure that the parts can be readily machined to fit together without exercising more than ordinary care.

Another object is to produce a mold that will cast a grid of minimum weight for given strength which will be free from fins and have an increased tendency to retain the paste in place.

A further object is to provide a mold that will extend the side ribs closer to the center of the grid to increase the conductivity without adding to the weight and with increased transverse strength.

Referring to the drawings:

Figure 1 is a plan view of the upper half of the mold shown in Fig. 2.

Fig. 2 is a section with the halves separated, the lower half only being completely machined, and the section of the upper half corresponding with the line A—A of Fig. 1.

Fig. 3 is a section similar to Fig. 2, excepting that the mold is completely machined and the halves are in operative position.

Fig. 4 is a section of the molds in the plane of the line B—B of Fig. 1, the halves being shown in operative position.

Fig. 5 is a side view of a grid cast in my improved mold.

Fig. 6 is a section on the line C—C, of Fig. 5.

Referring to Figs. 1 and 2, one-half of a mold 1 is rabbetted at 2 to form the frame of the grid. This rabbet or groove may be put in the molds in well known ways and inasmuch as it is not novel *per se* I have not illustrated the make-up of the mold to indicate

how this can be done. When the groove 2, however, has been formed I machine a plurality of triangular grooves 3 transversely of the mold, forming ridges 4. Then grooves 5 are machined in the bottom of the grooves 3 as shown in Fig. 3, and cross grooves 6 are cut to form the strengthening ribs of the grid.

The lower half of the mold is made similar to the upper half excepting that the grooves 3' and 5' are staggered in respect to the grooves 3 and 5 respectively.

When the two halves are placed together molten lead is poured into the gate 7 to fill the grooves 2, 5, 5' and 6. After cooling the halves are separated and the grid removed. The structure of the grid is clearly shown in Figs. 5 and 6. The novel feature of the grid resides in the shape of the bottom portion 8 of the ribs 9, this shape being such that the boundary of the cross-section of any rib shows a reentrant angle. Heretofore the ribs have been made with a flat base, and my improvement not only reduces the amount of lead required without decreasing the strength, but it also furnishes additional means for retaining the paste.

Also the prongs 9' project toward the center of the plate and provide means for the current reaching a greater amount of the active material by a path of good conductivity.

To a mechanic it would be a simple matter to machine the grooves 3 and 5 on a planer and when the two halves are finished, they will fit perfectly and cause no fins to be formed on the grid.

Having described my invention what I claim is:

A mold for battery grids comprising separable halves adapted, when fitted together, to define a series of communicating passages located in parallel planes, each of said passages containing a reentrant angle in the boundary of its cross-section.

In testimony whereof I hereunto affix my signature.

L. B. HILLS.
